FIG. 1 is a perspective view of a handheld electric salt spreader for use on sidewalks and driveways with detachable hopper showing my new design;

FIG. 2 is a side view with arm support unfolded (opposite side view is mirror image) thereof;

FIG. 3 is a back view thereof;

FIG. 4 is a front view showing the spout in a closed position thereof;

FIG. 5 is a top view thereof;

FIG. 6 is a bottom view thereof;

FIG. 7 is another side view with arm support folded thereof; and,

FIG. 8 is an enlarged front view showing the spout in an open position.
